[57] CLAIM

The ornamental design for a murette driver, as shown and described.

DESCRIPTION

FIG. 1 is a front elevational view of the murette driver of the present invention;

FIG. 2 is a back elevational view of the murette driver of FIG. 1;

FIG. 3 is a left side elevational view of the murette driver of FIG. 1;

FIG. 4 is a right side elevational view of the murette driver of FIG. 1;

FIG. 5 is a top plan view of the murette driver of FIG. 1;

FIG. 6 is a bottom plan view of the murette driver of FIG. 1; and,

FIG. 7 is an enlarged fragmentary perspective view of the

drive end of the murette driver of FIG. 1.
The shaft has been shown fragmentarily in FIGS. 1 through 4 to indicate an indeterminate length.
